UNITED STATES PATENT OFFICE.

SAMUEL SHOUP, OF CLIFTON HEIGHTS, PENNSYLVANIA.

SALES OR ORDER BOOK.

SPECIFICATION forming part of Letters Patent No. 499,046, dated June 6, 1893.

Application filed January 23, 1893. Serial No. 459,353. (No model.)

To all whom it may concern:

Be it known that I, SAMUEL SHOUP, a citizen of the United States, and a resident of Clifton Heights, Delaware county, Pennsylvania, have invented an Improved Sales or Order Book, of which the following is a specification.

The main object of my invention is to so construct a check sales-book, order book, check book or similar device as to facilitate the keeping of the record of the total sales, orders or checks, the detection and checking of possible errors and the auditing of the check or order slips. This object I attain by combining with a check sales-book or other such book of any suitable construction a superimposed movable tally sheet and one or more manifolding leaves or strips to reproduce upon the sales slips, check slips or order slips the entries made upon the tally sheet.

In the accompanying drawings, I have shown my invention as applied to a check sales-book, but it will be readily understood from the following description that my invention may equally well be applied to other books such as those for making out and keeping tally of orders.

Figure 1 is a plan view of one convenient construction of my invention which I have devised. Fig. 2 is a side view of the same. Fig. 3 is a longitudinal section showing the movable portion of the device elevated. Fig. 4 is a view of what may be termed a sales slip upon which entries have been made detached. Fig. 5 is a view of what would be the corresponding check slip upon which entries on the sales slip have been manifolded. Fig. 6 is a perspective view of the device without the sales or order book or tally sheet or manifolding leaves. Fig. 7 is a perspective view of the preferred form of construction of sales or order book. Fig. 8 is a view corresponding with Fig. 2, but of a modification.

The construction and arrangement of the leaves of the check sales-book or order book proper form no essential part of my present invention, which is applicable to, or capable of use in connection with various constructions of check sales-books or order books. In

applying my invention to a check sales-book, I prefer however, to use one of those constructions of books in which the successive leaves or folds are numbered in pairs for use in connection with a manifolding sheet to be 55 laid between the two leaves or folds of each pair so that the entries made on the top leaf or fold will be manifolded on the second. It is in connection with such a book that I have shown in the accompanying drawings, my 60 superimposed movable tally sheet combined with devices for carrying the movable tally sheet.

The devices for carrying the sheet are preferably mounted upon a tablet A of wood or 65 other suitable material which at the same time receives and holds the book B. This book may be retained in place upon the tablet A by any suitable means; in the present instance I have shown the book as provided 70 with a cardboard backing b projecting at one end beyond the body of the book and adapted to be fitted into and held by clips a on the tablet. The leaves or folds of the book are at the same time held in position also by the 75 devices carrying the movable tally sheet as will be hereinafter seen.

D is the superimposed tally sheet, which I prefer to make in the form of a traveling strip of paper wound onto two rollers d d' 80 mounted in a frame carried by the tablet, these two rollers d and d' being provided with thumb pieces or handles t t', by which to cause the paper strip to travel by winding off one roller onto the other. The opposite 85 ends of the tally sheet may be secured to the respective rollers in any suitable way, a convenient means being to slit the rollers, as shown in Fig. 3 for the convenient reception of the ends of the sheet to retain them for 90 winding up.

While I do not wish to restrict myself to any special form of frame for carrying the rollers of the traveling tally sheet I prefer to use the construction shown in Figs. 1, 2, 3 95 and 6. The frame shown is made in two parts, one D' which carries the roller d being fixed to the tablet, while the other part D' which carries the roller d' is hinged to the tablet or frame D', preferably through the 100

medium of the curved arms r . These arms may, as shown in Fig. 8, be a part of or fixed to the carrying frame, but the latter has preferably a hinge connection with the arms r at x , as shown in Figs. 1, 2, 3 and 6, so as to permit of a swinging movement of the frame D^2 upon these arms, both for the more convenient insertion and withdrawal of the sales or order book and also for the more convenient application and removal of the manifolding leaf or leaves which may be carried by this movable frame D^2 . In such case the manifolding leaf m which is ordinarily used to make the duplicate impression upon the second of each pair of leaves or folds of the sales or order book, as above described, may have its inner end secured to the clamp k , Figs. 3 and 6. I prefer also for the reason explained hereinafter to employ a strip m' of manifolding material immediately under the superimposed tally sheet and this strip of manifolding material may in such case conveniently be stretched across the under side of the frame D^2 and have its opposite ends secured by clamping strips k on the edges of the frame D^2 .

A spring S may be employed to tend to keep the frame D^2 with the tally sheet down upon the sales-book. In the drawings I have shown this spring as in the form of a spiral spring S , one end of which is connected to the pivot rod r' of the arms r which carry the movable frame, while the other end of the spiral spring bears in a notch in the roller d . This end of the spring S which bears in the notch of the roller d serves to hold the latter in its bearings in the frame D^2 , for when the end of the spring is lifted out of the notch in the end of the roller d the latter is free to be withdrawn laterally from the frame. Similarly the roller d' is normally held in its bearings in the frame D^2 by a spring finger f , the free end of which rests in a notch in that roller, but by raising the free end of the spring the roller is free to be withdrawn laterally from the frame.

When my invention is applied to a check-sales book, it may be printed in any well known or suitable manner, and the arrangement illustrated in Figs. 1, 4 and 5 is shown only by way of example. The superimposed tally sheet may also be printed in any suitable way and provided with any suitable number of columns for entries.

In the drawings I have shown the tally sheet as provided with five columns, of which the first may be used for the entry of the number of the sale made, or if preferred these numbers may be already printed thereon. The second column may be used for the entry of the salesman's number; the third for the number of the cash boy, or cup or basket; the fourth for the entry of the amount of cash received from the customer, and the fifth for the entry of the amount of the sale or sum charged for the article or articles sold. If desired the upper portion of the front slip as

shown in Fig. 4, may be arranged to be detached on the severing line y y , for the wrapper to apply to the wrapped-up bundle, and the back of this strip may be gummed for that purpose.

It will be seen from the foregoing description that by superimposing the tally sheet as described over the sales-book to insure the duplication of the tally sheet entries upon the check or sales slip, or both, I not only have the tally sheet in a convenient position for the entry of the items thereon by the salesman, but I also provide at least two additional simple and convenient means of checking errors. Thus when the check and sales slips go to the cashier or authorization clerk he has before him not only the usual entries upon those slips, but also a manifoldeed copy of the tally sheet entries, which he can instantly compare with the entries below on the check or sales slips; and furthermore when the check slip Fig. 4, goes to the wrapper with the articles to be wrapped up, the wrapper can also quickly compare the copy of the tally sheet entries with the entries on the sales or check slip and he will be particularly apt to make this his duty if he has to tear off the strip containing the copy of the tally sheet entries to put it upon the bundle or package. Thus, if the salesman has made any error in his tally sheet entries in any sale there is but very small chance of its escaping detection before the sale is completed. In addition to these advantages it will be seen that when the check slip is left with the cashier, carrying upon it a copy of the tally sheet entries as well as the sales slip entries, the auditing of the accounts is greatly facilitated.

I claim as my invention—

1. The combination of a check sales-book or other such book with a superimposed independently movable tally sheet in combination with manifolding means to duplicate the tally sheet entries upon the leaves of the book substantially as set forth.

2. The combination of a check sales-book or other such book with a superimposed independently traveling tally sheet and means for moving the successive entry spaces of the tally sheet into position over a portion of the book, and manifolding means to duplicate the tally sheet entries upon the leaves of the book, substantially as set forth.

3. The herein described device for a check sales-book or other such book, comprising a tablet for the reception of the book and a frame upon the tablet carrying rollers upon which a tally sheet may be wound with spaces for entries to be brought successively over a portion of the book and the entries duplicated on the leaves of the book by manifolding, substantially as set forth.

4. The herein described device for check sales-books or other such book, consisting of a tablet for the reception of the book and a

frame in two parts, of which one is movable, and carrying rollers for the tally sheet to be superimposed upon a portion of the book for the duplication of tally sheet entries on the latter by manifolding, substantially as set forth.

5. A check sales-book, or other such book, having leaves for the entry of sales, orders, or such items, and a coupon space for securing a manifold copy or copies of the tally

sheet entries, and a super-imposed tally sheet, substantially as described.

In testimony whereof I have signed my name to this specification in the presence of two subscribing witnesses.

SAMUEL SHOUP.
